UNITED STATES PATENT OFFICE

2,213,733

AIR CONDITIONING APPARATUS

Gerald E. Hicke, Chicago, Ill.

Application July 5, 1938, Serial No. 217,450

5 Claims. (Cl. 62—117)

My invention relates to an air conditioning apparatus particularly for moving vehicles, and one of the chief objects of my invention is to provide an improved apparatus which will provide moistened air for the carburetor of an internal combustion engine operating the compressor and at the same time provide air of a low dry bulb temperature for the radiator of the cooling system connected to the internal combustion engine.

Another object of my invention is to combine the internal combustion engine and the heat exchange cycle apparatus in one housing designed to be hung from the floor of a moving vehicle and wherein a single fan will move air not only through the evaporative condenser but past the radiator.

Another object of my invention is to arrange the position of the evaporative condenser and the radiator in the path of the air so that the air is passed, first, through the evaporative condenser and, secondly, through the radiator.

Another object of my invention is to provide moistened air for the carburetor of the internal combustion engine.

Another object of my invention is to vary the volume of air drawn through the condenser.

The foregoing and many other specific features of my invention are set forth in the following specification, where I describe what I consider the preferred embodiments of my invention. These are illustrated in the accompanying drawings where—

Figure 1 is a vertical cross section of the apparatus.

Figure 2 is a top plan view of the apparatus. Referring to Figures 1 to 2, inclusive, an evaporative condenser coil 10 together with the liquid receiver 25, the sprays 13', and line 26 from the liquid receiver to the evaporator 27, return line 28 to the compressor 16, constitutes the heat exchange cycle apparatus. The internal combustion engine 29 with the radiator 14, which is a part of the cooling system for said engine, and the carburetor 20 for said engine, constitute the internal combustion engine apparatus. All of this apparatus is enclosed within a housing comprising the sides 30 and 31, top 32, and the bottom 33. There are two air inlets 11 and 12.

50 and one air outlet 13. The air inlet 11 is designed for the entrance of air which is to be treated or moistened before passing over the evaporative condenser, then the radiator and then past the carburetor. The air inlet 12 is designed for the entrance of air which is to be

passed by the engine in its natural state without being conditioned. These inlets are located on opposite sides of the vehicle, and inlet 12 is provided with damper 35 which regulates the amount of air passing there-through. The air outlet 13 is located in the bottom of the housing and in a moving vehicle would be exhausted upon the roadbed.

The fan 18 operates to draw air from said inlets to the outlet at a constant cfm so that the opening of the inlet 12 will operate to draw more air through inlet 12 than through 11 because of friction, which is very desirable because there are localities such as found in the southwest part of the United States where the dry bulb temperatures are high, with an extremely low relative humidity, in which case the evaporative condenser, in addition to absorbing the condensing load, actually accomplishes evaporative cooling of the air, resulting in an excessive waste of water. To compensate for this inefficiency, the volume of the air passing by the condenser is reduced by opening the inlet 12 and by-passing a certain amount of unconditioned outside air past the power unit. The 25 housing is attached to the floor 22 of the moving vehicle, the sides of which are represented by the numerals 24 and the top 23.

A filter 34 is positioned in the inlet 11 so that the air supplied to the carburetor is not only moist but clean.

While I have described the foregoing preferred embodiments of my invention, I contemplate that many changes may be made without departing from the scope or spirit of my invention.

I claim:

1. In an air conditioning apparatus, the combination of heat exchange cycle apparatus comprising a compressor, an evaporator, an evaporative condenser, an internal combustion engine actuating the compressor, a radiator to cool said engine with a carburetor in connection therewith, a housing for said apparatus and engine with an air inlet, a filter and damper in said air inlet, an air outlet, a second dampered inlet, adjacent the engine, and a fan drawing air through said inlets, through the evaporative condenser and the radiator and past said carburetor to said outlet.

2. In an air conditioning apparatus for a moving vehicle, the combination of a heat exchange cycle apparatus comprising a compressor, an evaporator, an evaporative condenser, an internal combustion engine actuating the compressor, a radiator to cool said engine, a housing for said

apparatus and engine mounted beneath the floor of said vehicle with an air inlet on one side of the vehicle, a second air inlet on the other side of the vehicle, an outlet in the bottom of the housing, and a fan drawing air through said inlets, through the evaporative condenser and the radiator to said outlet.

3. In an air conditioning apparatus for a moving vehicle, the combination of a heat exchange cycle apparatus comprising a compressor, an evaporator, an evaporative condenser, an internal combustion engine actuating the compressor, a radiator to cool said engine, a housing for said apparatus and engine mounted beneath the floor of said vehicle with an air inlet on one side of the vehicle for air to be moistened, a second air inlet on the other side of the vehicle, an outlet in the bottom of the housing, and a fan drawing air through said inlets, through the evaporative condenser and the radiator to said outlet.
- 10 4. In an air conditioning apparatus for a moving vehicle, the combination of a heat exchange cycle apparatus comprising a compressor, an evaporator, an evaporative condenser, an internal combustion engine actuating the compressor, a radiator to cool said engine, a housing for said apparatus and engine mounted beneath the floor of said vehicle with an air inlet on one side of the vehicle, a second air inlet on the other side of the vehicle, an outlet in the bottom of the housing, means to vary the flow of air through 15 said inlets, and a fan drawing air through said inlets, through the evaporative condenser and the radiator to said outlet.
- 15 5. In an air conditioning apparatus for a moving vehicle, the combination of a heat exchange cycle apparatus comprising a compressor, an evaporator, an evaporative condenser, an internal combustion engine actuating the compressor, a radiator to cool said engine, a housing for said 20 apparatus and engine mounted beneath the floor of said vehicle with an air inlet on one side of the vehicle, a second air inlet on the other side of the vehicle, an outlet in the bottom of the housing, and a fan drawing air through said inlets, through the evaporative condenser and the radiator to said outlet.

GERALD E. HICKE.
